UNITED STATES PATENT OFFICE.

JOSEPH R. GORDON, OF BALDWIN, NEW YORK, ASSIGNOR TO AMERICAN NUMBERING MACHINE COMPANY, OF BROOKLYN, NEW YORK, A CORPORATION OF NEW YORK.

DIE-PRESSING APPARATUS.

Application filed September 29, 1923. Serial No. 665,697.

To all whom it may concern:

Be it known that I, JOSEPH R. GORDON, a citizen of the United States, and a resident of Baldwin, county of Nassau, and State of New York, have invented a certain new and useful Die-Pressing Apparatus, of which the following is a specification.

The invention relates to apparatus for forming characters on the wheels or discs of numbering machines, cash registers, calculating machines, and the like.

The objects of the invention are to provide an apparatus which will be cheap to construct, of economical operation; of simple, strong and rugged construction; which will not easily get out of order; which is easy to repair, and by means of which a plurality of characters or groups of characters may be formed simultaneously.

One embodiment of the invention is illustrated in the accompanying drawings, in which like parts in all of the several figures are designated by corresponding characters of reference, and in which

Fig. 1 is a top plan view of the preferred embodiment of the invention, a portion of the mechanism being removed.

Fig. 2 is a detail side elevation of a form of stop.

Fig. 3 is a plan view of a form of holder.

Fig. 4 is a section on the line 4—4 of Fig. 1, a portion of the apparatus being in side elevation.

Figs. 5, 6 and 7 are diagrams showing various positions assumed by a matrix bar in carrying out the process of the apparatus, and

Fig. 8 is a detail section taken on the line 6, 6 of Fig. 1.

In carrying out the invention a base comprising parallel sides 1, 1 is employed. The base is preferably mounted on a bench or pedestal, and carried by the base is a circular bed plate 2.

The upper surface of the bed plate is provided with a central cylindrical chamber 3 and with an annular shoulder 4 on its outer periphery, said shoulder and recess defining the boundaries of an annular table 5, and the table is formed with an annular shoulder 6 around its outer periphery.

The table 5 is provided with a circular series of radially arranged rectangular recesses 7 each open at the top and at each radial end. That portion of the table in

which the recesses 7 are located is narrow compared with the distance between the periphery of the chamber 3 and the shoulder 4, on which latter is carried an annular wall 8, and an annular recess 9 is thus formed between the wall and the partitions between the recesses 7.

Within each recess 7 is slidably disposed a parallelopipedon formed block 10 having a threaded bore 11 in which is mounted an externally and internally threaded nut 13. The female threads 14 of the nut are of a pitch different from the male thread 15 thereon.

Mounted in the annular wall 8 is a plurality of stub shafts 16 each shaft being in radial alignment with the bore of one of the nuts 13. Mounted on each shaft 16 and in the annular recess 9 is a bevel pinion 17. Each stub shaft has a threaded extension 75 engaging the female thread of a nut. Each nut is provided with an unsymmetrical head 18 whereby the nut may be rotated to adjust the positions of the blocks 10 axially toward and away from the center of the bed plate 2. 80

Lying within the recess 9 and in mesh with all of the pinions 17 is a circular, bevel rack 19. An annular plate 20 rests upon the rack 19 and the partitions between the recesses 7, and covers the said recesses, and 85 retains the blocks 10 in position. A ring 21 bolted to the wall 8 retains the rack 19 and plate 20 in position.

A stub shaft 22 is journaled in the wall 8 and one of a triangular partition and carries a bevel pinion 23 which meshes with the rack 19. One end of the shaft 22 projects beyond the outside periphery of the wall and carries arms 24 or the like whereby the rack may be revolved around the center of 90 the base plate, and motion be transmitted to all of the pinions 17 whereby all of the blocks may be simultaneously and equally moved radially toward or away from the center line of the base plate as the shaft 22 95 is rotated in one direction or the other.

Each block 10 is provided at its inner end with a pair of spaced, perforated lugs 25, and between each pair of lugs is pivoted a matrix lever 26. The levers are in radial 105 arrangement, and when a number of them are employed or when they extend well toward the center, the sides may be beveled, as shown in Fig. 1.

In the embodiment of the invention illus- 110

trated each lever 25 has its free end formed to an arc struck from the pivotal point of the lever. The top and bottom sides of the free extremity of the lever are rounded to 5 circular form, the circle being struck from the point at the center of the arc-shaped face 27 of the lever, and the top and bottom arcs overhang the face 27 as illustrated.

Into the face 27 of the lever is cut, in 10 intaglio, the character, group of characters or other design which it is designed to have formed on the disc, wheel or other object.

The base plate is provided with a central 15 perforation 28 which forms a bearing for a plunger 29. The lower projecting end of the plunger carries a grooved fitting 30 which is engaged by the forked end of a lever 31 of the first class pivoted in the side members 1, 1. The opposite end of the lever 20 is U-shaped and engages an eccentric 32 mounted on a shaft 33 to which power may be applied in any desired manner.

The plunger 29 extends through the bed plate 2 and near its upper end is provided 25 with a flange 34, and carried on the flange by means of a plurality of coil springs 35 is a movable collar 36.

The upper end of the plunger is bored 30 and tapped for the reception of a tap bolt 37 having two shoulders 38 and 39 and a 35 polygonal head. On the bolt 37 is threaded the disc 40 to be operated upon. Washers 41 and 42 are placed one on either side of the disc 40, and between the washer 42 and 40 the shoulder 38 is a washer 43, the latter, and the shoulder 39 forming a peripheral 45 groove 44 around the bolt 29 for a purpose to be hereinafter described.

The operation is as follows:— 40 As shown in Figs. 1 and 2 the apparatus is in the position after the process has been carried out. The shaft 22 is rotated in the anti-clockwise direction, the rack 19 is revolved causing the blocks 10 and levers 26 to be simultaneously moved away from the center, thus releasing the disc 42.

The stud bolt 29 and with it the washers 41, 42 and 43, and the disc 40 are removed 45 from the plunger 29. Because of the pressure which has been applied to the surface of the disc, the latter will be frozen to the stud bolt. The pivoted leaves 45, and 46 of the holder 47 are swung apart and then closed around the stud shaft, the opening 48 engaging the recess 44 between the shoulder 39 and washer 43. The stud bolt may now 55 be driven out of the disc 40 and the washer.

The washers are now reassembled on the 60 stud bolt with a new disc between the washers 41 and 42, and the stud bolt is positioned on the plunger as before. The shaft 22 is now rotated in the clockwise direction to move the levers 26 inward to contact with the new disc 40. When the faces 27 of the 65 levers 26 engage the surface of the discs, a

knob 49 is slipped down over the end of the bolt 37 and rests upon the free ends of all of the levers 26.

Power is applied to the shaft 33 and the plunger 29 is given a reciprocating motion 70 axially in its bearing. The operator will apply pressure downward on the knob 49 whereby the levers 26 rock in unison with the oscillations of the plunger.

During this operation the operator continues to feed the blocks 10 and levers 26 toward the center by turning the shaft 22 in the clockwise direction. The rolling kneading or knuckling movements of the faces 27 of the matrix levers will cause the 80 metal of the disc 40 to flow, as it were, into the intaglio characters cut in the faces whereby the characters in relief, will be formed on the edge of the disc.

The movement of the levers inward is 85 limited by the engagement of a finger 50 on the shaft 22 with a stop 51 carried by the ring 21.

When the metal of the disc begins to enter the matrices, the hand of the operator may 90 be removed from the knob 49, or the knob may be removed, and the bite of the levers against the disc will cause the levers to pivot.

To adjust the apparatus to operate on 95 discs of various sizes, a wrench may be applied to the heads 18 of the nuts 15 and the blocks 10 may be set to any diameter desired. The ring 21 is provided with opening 100 52 for this purpose.

It will be understood that when it is desired to cut or press characters in the disc, the matrix characters must be in relief.

Preferably the levers should be arranged 105 in oppositely disposed radially aligned pairs whereby the thrusts will be evenly distributed, and there will be no strains placed upon the plunger 29.

When it is desired to produce a disc having an uneven number of characters such, 110 for example, as the day of the month disc of a time stamp, the levers should be even in number, and the face 27 of one of them should be blank.

The invention is not, however, limited to 115 the use of an even number of matrix levers, as an uneven number may be employed if desired.

In the drawings the plunger 29 is illustrated as operating vertically but it is to be 120 understood that this is not essential to the operation. The reciprocations of the plunger may be in any direction so long as the feeding movements of the levers are at right angles to the axis of the plunger.

In accordance with the provisions of the patent statutes the principle of the invention has been described, together with the apparatus which is now considered to represent the best embodiment thereof, but it 125 130

is desired to have it understood that the apparatus shown is merely illustrative, and that the invention may be carried out in other ways.

5. The invention having been described, what is claimed as new and desired to be secured by Letters Patent, is as follows:

1. Apparatus of the character described, comprising a body, means for giving to the body a reciprocating movement, and means having a biting engagement with the surface of the body whereby the said engaging means will be reciprocated by and with the body.

15. 2. Apparatus of the character described, comprising a body, means for giving to the body a reciprocating movement, means engaging the surface of the body whereby the said engaging means will be reciprocated by and with the body, and means for moving the engaging means relatively to the body.

3. Apparatus of the character described, comprising a body, means for giving to the body a reciprocating movement, means engaging the surface of the body whereby the said engaging means will be reciprocated by and with the body, and manually operated means for moving the engaging means relatively to the body.

30. 4. Apparatus of the character described, comprising a body, means for reciprocating the body, a pair of levers having their free ends engaging the body at diametrically opposite points, there being rolling contact between the body and levers, and means for reciprocating the body in the direction at right angles to the axes of the pivots of the levers, the engagement of the levers with the body imparting pivotal movement to both levers.

45. 5. Apparatus of the character described, comprising a body, means for reciprocating the body, a pair of levers having their free ends engaging the body at diametrically opposite points, there being rolling contact between the body and levers, means for reciprocating the body in the direction at right angles to the axes of the pivots of the levers, and means for feeding the levers toward each other to cause a biting contact between the levers and body whereby one of said elements will be caused to enter the other, the engagement of the levers with the body imparting pivotal movement to the levers.

55. 6. Apparatus of the character described, comprising a base plate, a plunger adapted to reciprocate through the base plate, a plurality of slid able blocks grouped in circular arrangement around the plunger, a lever pivoted to each block, said levers extending radially toward the axial line of the plunger, a body carried by the plunger, the free ends of said levers engaging the periphery of the body, a nut carried by each block, a bolt engaging each nut, and means for simultane-

ously rotating the bolts to feed the nuts and levers toward the axial line of the plunger.

7. Apparatus of the character described, comprising a base plate, a plunger adapted to reciprocate through the base plate, a plurality of slid able blocks grouped in circular arrangement around the plunger, a lever pivoted to each block, said levers extending radially toward the axial line of the plunger, a body carried by the plunger, the free ends of said levers engaging the periphery of the body, a nut carried by each block, a bolt engaging each nut, a pinion carried by each bolt, a rack engaging all of the pinions, and means for moving the rack to simultaneously move the blocks and levers toward or away from the axial line of the plunger.

8. Apparatus of the character described, comprising a base plate, a plunger adapted to reciprocate through the base plate, a plurality of slid able blocks grouped in circular arrangement around the plunger, a lever pivoted to each block, said levers extending radially toward the axial line of the plunger, a body carried by the plunger, the free ends of said levers engaging the periphery of the body, a nut carried by each block, a bolt engaging each nut, a pinion carried by each bolt, a circular rack engaging all of the pinions, and manually operated means for moving the rack to simultaneously move the blocks and levers toward or away from the axial line of the plunger.

9. Apparatus of the character described, comprising a base plate, a plunger adapted to reciprocate through the base plate, a plurality of slid able blocks grouped in circular arrangement around the plunger, a lever pivoted to each block, said levers extending radially toward the axial line of the plunger, a body carried by the plunger, the free ends of said levers engaging the periphery of the body, a nut having screw threads on its outer periphery and engaging screw threads in each block, a bolt engaging each nut, and means for simultaneously rotating the bolts to feed the nuts and levers toward the axial line of the plunger, said nut having means whereby the same may be rotated relatively to the block and bolt.

10. Apparatus of the character described, comprising a circular base plate, there being a circular series of radially arranged open ended recesses in the bed plate, a block slidably mounted in each recess, a lever pivoted to each block and extending radially toward the center of the base plate, there being a threaded bore in each block, a nut having screw threads on its outer periphery, said threads engaging the threads of the block, a bolt engaging the interior threads of the nut, a bevel pinion secured to each nut, a circular bevel rack engaging all of the bolt pinions, a stub shaft, a bevel pinion on the stub shaft, said pinion engaging the rack,

a plunger located centrally in the base plate, a body clamped to the plunger, means applied to the stub shaft for rotating the same to rotate the rack and bolt pinions to simultaneously move all of the blocks radially inward to force the free ends of the levers into intimate engagement with the body, and means for reciprocating the plunger whereby the levers may, by their engagement with the body, be rocked on their pivots.

11. Apparatus of the character described, comprising a circular base plate, there being a circular series of radially arranged open ended recesses in the bed plate, a block slidably mounted in each recess, a lever pivoted to each block and extending radially toward the center of the base plate, there being a threaded bore in each block, a nut having screw threads on its outer periphery, said threads engaging the threads of the block, a bolt engaging the interior threads of the nut, a bevel pinion secured

to each nut, a circular bevel rack engaging all of the bolt pinions, a stub shaft, a bevel pinion on the stub shaft, said pinion engaging the rack, a plunger located centrally in the base plate, a body clamped to the plunger, means applied to the stub shaft for rotating the same to rotate the rack and bolt pinions to simultaneously move all of the blocks radially inward to force the free ends of the levers into intimate engagement with the body, and means for reciprocating the plunger whereby the levers may, by their engagement with the body, be rocked on their pivots, there being a character sunk in the free end of each lever whereby the movement of the levers toward the center and the rocking movement of the levers relatively to the body will force the material of the body into the sunken portions of the ends of the levers.

This specification signed this 26th day of September, 1923.

JOSEPH R. GORDON.
